(57) **CLAIM**

The ornamental design for a jockey wheel clamp, as shown and described.

DESCRIPTION

FIG. 1 is a front perspective view in clamping configuration from above right;

FIG. 2 is a rear perspective view in clamping configuration from below left;

FIG. 3 is a front elevation in clamping configuration;

FIG. 4 is a rear elevation in clamping configuration;

FIG. 5 is a side elevation in clamping configuration from right;

FIG. 6 is a side elevation in clamping configuration from left;

FIG. 7 is a plan view from above in clamping configuration;

FIG. 8 is a plan view from below in clamping configuration; and,

FIG. 9 is a front perspective view from above right in open configuration.

The broken lines depict portions of the jockey wheel clamp that form no part of the claimed design.
